[57] CLAIM

The ornamental design for an emergency roadside sign, as shown and described.

DESCRIPTION

FIG. 1 is a front elevation view of the emergency roadside sign of the present invention;

FIG. 2 is a back elevation view of the emergency roadside sign of FIG. 1;

FIG. 3 is a left side elevation view of the emergency roadside sign of FIG. 1;

FIG. 4 is a right side elevation view of the emergency roadside sign of FIG. 1;

FIG. 5 is a top plan view of the emergency roadside sign of FIG. 1;

FIG. 6 is a bottom plan view of the emergency roadside sign of FIG. 1; and,

FIG. 7 is a front elevation view of the emergency roadside sign of FIG. 1 in a collapsed condition; and,

FIG. 8 is a left side elevation view of the emergency roadside sign of FIG. 1 in a collapsed condition; and,

FIG. 9 is a right side elevation view of the emergency road sign of FIG. 1 in a collapsed condition.

The crosshatching is fragmentarily shown for convenience of illustration.

The broken lines are shown for illustrative purposes only and form no part of the claimed design.
